UNITED STATES PATENT OFFICE.

DAVID G. JOHNSTON, OF CLAYWORKS, IOWA.

FRAME FOR OPENINGS IN BUILDINGS.

1,044,533.

Specification of Letters Patent.

Patented Nov. 19, 1912.

Application filed November 12, 1909, Serial No. 527,719. Renewed September 30, 1912. Serial No. 723,238.

To all whom it may concern:

Be it known that I, DAVID G. JOHNSTON, a citizen of the United States, residing at Clayworks, in the county of Webster and State of Iowa, have invented a certain new and useful Frame for Openings in Buildings, of which the following is a specification.

The object of my invention is to provide a frame of simple, durable and inexpensive construction, made out of a single piece of structural channel bar for the purpose of forming a frame for window and door openings in buildings particularly silos which may be readily and easily placed in position and firmly and securely held therein, and further to provide means whereby said frames may be readily and easily placed in building material and after being so placed may be firmly and securely held therein by pouring concrete in the spaces provided for it at the sides of the frame, and also to provide means whereby said frames may be used for connecting strengthening and reinforcing wires or rods in the walls of the building.

My invention consists in certain details, in the construction, arrangement and combination of the various parts of the device whereby the objects contemplated are attained, as hereinafter more fully set forth, pointed out in my claims and illustrated in the accompanying drawings, in which—

Figure 1 shows a perspective view of a frame embodying my invention. Fig. 2 shows a vertical, central, sectional view of same, and Fig. 3 shows a horizontal, sectional view of same with the adjacent portions of a wall shown in position therein.

Referring to the accompanying drawings, the body portion of the frame is seen to be composed of a single piece of structural channel bar. The flanges of the channel bar are cut at the corners so that the central portion of the channel bar may be bent to thereby produce a frame composed of a single piece of channel bar.

In the drawings the numeral 10 is used to indicate the bottom of the frame and 11, the side flanges of the bottom. 12 indicates the body portion of the sides of the frame and 13 the flanges of the sides. 14 indicates the body of the top of the frame, and 15 the flanges thereof. The flanges of the channel bar at the top are cut away for a short distance, thus leaving the central portion of

the channel bar at 16 projecting beyond the flanges. This is bent down over the adjacent body portion of the channel bar 12 as shown in Fig. 2, and connected by rivets 17. Secured to the central portion of the body portion 12 at each side are two spacing and anchoring rods 18, the ends of which are extended through the part 12 and secured thereto, and the central portions of said rods stand spaced apart from the side 12 and lie parallel with it. These rods extend outwardly from the parts 12 of the frame handle about half the distance of the width of the flanges 13 as clearly shown in Fig. 2. On the interior of the frame, I have provided sheet metal stops 19 riveted in position for engaging a door or window placed in the frame.

In Fig. 3 of the drawings, I have illustrated a portion of a building wall 20 in position between the flanges 13 of the frame and in said wall are the reinforcing wires or rods 21 connected with the rods 18. In said figure the dotted lines 22 represent the division line between the wall proper and the concrete filler poured between the wall and the frame, the said concrete filler being indicated in said figure by the reference numeral 23.

In practical use it is obvious that the frames may be manufactured at a minimum of expense and that they will be extremely strong and durable when placed in position. The spacing and anchoring rods 18 perform several functions, first in laying up the main walls relative to the frames. The building material such as brick, tile, or concrete is held spaced apart from the body portions of the sides 12 by means of said rods, these providing a space to receive concrete. Furthermore said rods also provide a convenient anchorage for strengthening and reinforcing wires 21 which may be tied to said rods during the construction of the wall. After the wall has been completed up to the top of the frame, the operator then pours concrete in wet condition into the space between the walls and the sides of the frame so that said concrete material completely fills all of the space between the wall and frame, thus making it air tight and preventing the entrance of moisture which would tend to rust the metal, and at the same time firmly securing the frame to the concrete by means of the rods 18, and also firmly securing the reinforcing wires 21

to the rods 18. Therefore when the concrete has set and hardened, a perfect joint will be provided between the frame and the wall and the concrete material between the flanges will also strengthen and reinforce the frame itself in such a manner that it will be held perfectly firm and true against all ordinary strains to which said structures are subjected.

10 I claim as my invention—

1. A frame for openings in buildings, composed of channel bars with flanges extending outwardly, rods on each side of said frame between the flanges of the channel bars secured to the central portion of the channel bars at points spaced apart therefrom parallel thereto, said rods being designed to rest adjacent to the frame of the building and to hold the same spaced apart 20 from the central portion of the channel

bars and also to serve for the attachment of anchoring rods.

2. A frame for openings in buildings, composed of channel bars with the flanges extending outwardly, rods on each side of 25 said frame between the flanges of the channel bar secured to the central portion of said channel bar parallel thereto at points spaced apart from said central portion at a distance less than the width of the flanges, 30 said rods being designed to rest adjacent to the frame of a building and to hold the same spaced apart from the central portion of the channel bar and also to serve for the attachment of anchoring rods.

Des Moines, Iowa, October 18, 1909.
DAVID G. JOHNSTON.
